GOLF CLUB

James A. Karns, Akron, Ohio, assignor to Fawick
Flexi-Grip Company, Akron, Ohio, a corpora-
tion of Ohio

Application June 4, 1949, Serial No. 3,048

Term of patent 14 years

(Cl. D34—5)

To all whom it may concern:

Be it known that I, James A. Karns, a citizen of the United States, residing at 974 Greenwood Avenue, Akron, Ohio, have invented a new, original, and ornamental Design for a Golf Club, of which the following is a specification, reference being had to the accompanying drawing, forming a part hereof.

Fig. 1 is a side elevational view of the golf club, showing my new design;

Fig. 2 is a cross-sectional view thereof taken on line 2—2 in Fig. 1;

Fig. 3 is a fragmentary cross-sectional view thereof taken on line 3—3 of Fig. 2; and

Fig. 4 is a fragmentary elevational view, to an enlarged scale, of the shaft of the golf club shown in Fig. 1.

The shaft of the golf club shown in Fig. 1 is partly broken away for convenience of illustration.

The dominant features of my new design are shown in solid lines in the drawing.

I claim:

The ornamental design for a golf club, as shown and described.

JAMES A. KARNS.
